UNITED STATES PATENT OFFICE.

JAMES C. DRAKE, OF ROCHESTER, MINNESOTA, ASSIGNOR TO SEARS, ROEBUCK AND COMPANY, OF NEW YORK, N. Y., A CORPORATION OF NEW YORK.

SOUND-BOX COUPLING FOR TALKING-MACHINES.

1,369,793.

Specification of Letters Patent.

Patented Mar. 1, 1921.

Application filed April 17, 1917. Serial No. 162,747.

To all whom it may concern:

Be it known that I, JAMES C. DRAKE, a citizen of the United States, residing at Rochester, in the county of Olmsted and State of Minnesota, have invented certain new and useful Improvements in Sound-Box Couplings for Talking-Machines, of which the following is a specification, reference being had therein to the accompanying drawing.

My invention relates to sound recording and reproducing machines and especially sound box mountings therefor.

An object of my invention is to provide a simple and effective arrangement for mounting the same sound box upon the tone arm of a machine of the above type, in different positions or adjustments for use with either the laterally or perpendicularly undulating type of record.

Another object of my invention is to provide means for connecting the interior of the diaphragm chamber of the sound box with the interior of the tone arm whereby vibrations extraneous to and of the sound box body shall not be communicated to the tone arm and a firm and positive connection between separable tubular sections shall be afforded without the necessity for machining the parts to an accurate fit with consequent increase in cost of production.

Other objects of my invention reside in the novel construction, combination and arrangement of parts hereinafter described and particularly pointed out in the appended claim.

I attain my objects in the following manner: First, I provide the tone arm with a short terminal fitting, which may be pivoted to the arm to have play upward and downward with respect thereto. This fitting is adapted to receive either one of two short adapters or attachments, to which the sound box may be attached, one of the adapters holding the box in an inclined position to play from a vertically cut record, while the other adapter holds the box upright with the plane of its diaphragm parallel to the axis of the tone arm and perpendicular to the surface of the record, for playing laterally cut records. Second, I provide the neck of the sound box with a rubber gasket arranged to be interposed between said neck or flange of the sound box and the metal

part of the fitting or adapter to which it is attached.

My invention is illustrated in the accompanying drawings in which—

Figure 1 is a top plan view of a tone arm with one form of sound box connecting elbow attached and with the sound box removed.

Fig. 2 is a side elevation of the same.

Fig. 3 is a fragmentary side view of the jointed end of the tone arm.

Fig. 4 is a top plan view of the elbow link adapter for use with laterally undulating records.

Fig. 5 is a side view of Fig. 4.

Fig. 6 is a side view of the adapter for use with perpendicularly undulating records.

Fig. 7 is a side view of the sound box mounting assembled with the adapter of Fig. 6.

Referring to the details of the drawings, 1 indicates the body of the tone arm supported by the elbow 2 which is pivoted at 3 to permit the tone arm to swing horizontally. The hollow elbow 2 communicates with a suitable horn or amplifier not shown, through the flanged collar 4. The tone arm is provided at its free end with a short pivoted tubular section 5 forming the terminal of the tone arm proper. The tone arm terminal 5 is provided with a laterally projecting stud 6 and is split or slotted at 7 passing through the center of the stud 6. By the provision of the slot 7 a certain amount of expansion of the end of the section 5 is afforded, and to increase the resiliency of the tube at this locality, I reduce the thickness of the wall of the tube as indicated at 8 from the free end inward to a depth slightly greater than that of the slot 7, as indicated by the dotted line 9. Preferably the stud 6 is embossed in the tube 5, although it may of course be cast or otherwise formed upon the tube. Also if desirable other slots like 7 may be formed in the tube, although in practice it is found that by reducing the thickness of the wall of the tube as before stated, a single slot is sufficient.

For the purpose of connecting the sound box to this tone arm terminal 5, I provide a pair of interchangeable elbow link adapters 10 and 11, shown detached in Figs. 4, 5 and 6, which elbows are alike in all re-

spects except that they vary somewhat in length and angular adjustment. This variation, as will later appear, is for the purpose of connecting the same sound box, or 5 sound boxes of the same type, with the tone arm in different angular relations thereto according to the type of record to be played. For example, the adapter 10 is for use with 10 records of the laterally-undulating-groove type, while the adapter 11 is for use with records of the perpendicularly-undulating-groove type.

In Figs. 1 and 2, I have shown the adapter 10 in operative connection with the tone 15 arm terminal 5, Fig. 1, without the sound box, and Fig. 2 with the sound box 12. The adapter 10 consists of a tube bent in the form of a rectangular elbow having one end reduced as at 13 to fit within the tone 20 arm terminal 5 and forming a shoulder 14. Mounted on the reduced portion 13 and projecting outwardly and radially therefrom is a threaded shank 15 which is held fixed in the elbow, preferably by a soldered head 16. 25 This threaded shank is of such diameter as to enable it to pass into the slot when the reduced end 13 of the elbow is passed into the tone arm terminal 5 and is so spaced from the shoulder 14 that upon the engagement 30 of the shoulder with the end of the tone arm terminal, the said shank will be positioned in the slot coaxially with the stud 6. A binding or lock nut 17 is carried by the shank in threaded engagement there- 35 with and is provided with a socket 18 on its end surface for engagement with the stud 6. The engaging surfaces of the parts 5 and 13 are so proportioned in relation to each other that their engagement causes a slight distortion or expansion of the slotted end 40 of the member 5 so that the resiliency of the reduced portion 8 together with the binding effect of the lock nut 17 will afford a tight non-vibrating connection, the engagement 45 of the stud 6 with the socket 18 forming a positive lock. The outer end 19 of the adapter 10 is reduced to form a shoulder 20, the reduced portion having a longitudinal slot 21 therein which acts as a guide for 50 positioning the sound box. The arrangement of the sound box terminal for engagement with this outer end 19 of the elbow is shown in Fig. 7 and consists of the tubular extension 22 fitted with a bushing 23 of rubber or other suitable elastic sound insulating 55 material. The inside diameter of the elastic bushing 23 is slightly less than the outside diameter of the reduced end 19 of the adapter 10 so as to fit thereover with a slight 60 compression of the bushing. A guiding stud or shank 24 is carried by the tubular extension 22 and extends inwardly and radially therefrom through the bushing a sufficient 65 distance to engage with the slot 21 in the end of the elbow. This guide shank 24 is so

positioned that when the sound box is coupled onto the elbow, the axis of the stylus point 25 will take the angular position indicated in Fig. 2. Thus, as shown in Fig. 2, when the sound box is connected with 70 the tone arm by the adapter 10, the parts are in the correct relative adjustment for playing records of the laterally-undulating-groove type.

The adapter 11 has its coupling ends 26 75 and 27 formed identically like the corresponding ends 13 and 19 of the adapter 10, the end 26 being reduced and provided with a threaded shank 28 and socketed lock nut 29 arranged to coöperate with the tone arm 80 terminal 5, and the end 27 reduced and provided with a slot 30 for coöperation with the coupling means carried by the sound box 12, so that the ends 27 and 28 may co-operate with the tone arm terminal and the 85 sound box terminal interchangeably with the corresponding portions of the adapter 10. The body of the adapter 11 is made shorter than that of the adapter 10 and is given the form of a reflex or double curve 90 so that when it is used to connect the sound box 12 to the tone arm terminal 5 as indicated in Fig. 7, the sound box will be positioned transversely with the axis of the tone arm and at the proper incline or angle for 95 playing records of the perpendicularly-undulating-groove type, the distance between the coupling ends 27 and 28 being such that the stylus point 25 will be at the same distance from the axis on which the tone arm 100 is pivoted as when the elbow 10 is used.

While I have shown the tone arm terminal 5 pivoted to the tone arm body, it is to be understood that in certain types of tone arms such as those which are pivoted to move 105 vertically as well as horizontally, the tone arm terminal may be integral with or otherwise connected in fixed relation to the tone arm body.

From the above it will be seen that I have 110 provided a simple and effective means for connecting the sound box with the tone arm in different positions for coöperation with different types of records, respectively. By the use of the interchangeable adapters herein shown and described, each of the two adjustments is fixed and determined by the form given the particular adapter to be used with that adjustment so that there is no possible error in making the adjustment 120 so long as the proper link is used.

Having thus described my invention what I claim and desire to secure by Letters Patent is:—

A tone arm having a stub tube constituting a continuation of said arm, a transverse joint connecting one end of said tube with the arm, a sound box, and a pair of interchangeable elbow members each provided at one end with a fitting to make rigid and 130

non-rotatable connection with the sound box, and at the other end with means to automatically set and to hold rigidly the respective elbow in connection with the free end 5 of the movable stub tube of the tone arm at right angles with the other elbow, one elbow having a double curve, the other a single

curve, whereby the sound box may be held on the stub tube and move therewith and thereon, in either of two positions, with its 10 diaphragm in planes at right angles to each other.

In testimony whereof I affix my signature.
JAMES C. DRAKE.
